US0D1052790S

(12) **United States Design Patent** (10) Patent No.: **US D1,052,790 S**
(45) Date of Patent: ** Nov. 26, 2024

(54) **TAILLIGHT ASSEMBLY FOR MOTOR VEHICLE**

(71) Applicant: **Dr. Ing. h.c. F. Porsche Aktiengesellschaft**, Stuttgart (DE)

(72) Inventor: **Woosung Chung**, Stuttgart (DE)

(73) Assignee: **Dr. Ing. h.c. F. Porsche Aktiengesellschaft** (DE)

(**) Term: **15 Years**

(21) Appl. No.: **29/815,285**

(22) Filed: **Nov. 12, 2021**

(30) **Foreign Application Priority Data**

May 14, 2021 (EM) 008539845-0011

(57) **CLAIM**

The ornamental design for a taillight assembly for motor vehicle as shown and described.

DESCRIPTION

FIG. 1 is a perspective view of a taillight assembly for motor vehicle showing my new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken line showing of the taillight assembly for motor vehicle is for the purpose of illustrating portions of the taillight assembly for motor vehicle and forms no part of the claimed design.

1 Claim, 7 Drawing Sheets
